UNITED STATES PATENT OFFICE.

THOMAS MALCOLM DAVIDSON, OF BROMLEY, ENGLAND.

CLOSURE FOR RETORTS.

Application filed May 17, 1923, Serial No. 639,647, and in Great Britain July 13, 1922.

This invention relates to closures or discharge valves for retorts and more particularly for the closure of the bottom of vertical or inclined retorts intended for the distillation of solid carbonaceous substances.

The invention has among its objects to provide a perfectly gas tight closure involving the use of a door which can be readily operable for opening or closure, and which does not require the use of any bolts or other devices that need unfastening or fastening on the opening or closure.

The invention comprises the constructional features hereinafter described and is illustrated in the accompanying drawings in which—

Figure 1 represents a sectional elevation of a closure or discharge valve for retorts according to the invention.

Figure 2 is a plan corresponding to Figure 1, and

Figure 3 is a corresponding end elevation.

In carrying the invention into effect as illustrated in the accompanying drawings, a door *a* in the form of a cylindrical sector such as hereinbefore described is mounted partially to rotate upon its axis within a semi-cylindrical casing *b* having its cylindrical wall *b*³ provided with oppositely disposed flanges *b*¹ by means of which the parallel disposed lateral walls *b*² may be secured to the cylindrical wall *b*³ by such means as rivets. The casing *b* is thus open at its lower end which is mounted and secured within a dish-shaped receptacle *c* within which a liquid such as water is maintained above the level of the lower edge of the respective cylindrical and lateral walls of the casing *b*.

It will thus be understood that the casing *b* may be made of plate or sheet metal as may also the door *a* and the dish-shaped receptacle *c*, but no limitation is made to the utilization of plate or sheet metal.

The door *a* may be formed of a sheet bent in the form of a sector having a cylindrical wall *a*¹ and two oppositely disposed and parallel walls *a*² and a radial wall *a*³ the respective walls being integrally formed or secured together, and the door so formed may be carried upon arms *d* which may be integrally formed or mounted upon the axle *e*, which is carried in suitable bearings or stuffing boxes in the respective longitudinal walls *c*¹ of the dish-shaped receptacle *c*. One end of the axle *e* may be provided of a

square section for the reception of a wheel or handle by means of which the door may be rotated through an angle of 90° to bring it from the closed position indicated in full lines in Figure 1 into the open position indicated in dotted lines in that figure, whereby the retort *f* beneath which the casing *b* is mounted may thus be open or closed.

The upper cylindrical wall *b*³ of the casing *b* is on one side interrupted for the reception of a tubular part or fitting *b*⁴ of a form corresponding to that of the lower part of the retort *f*, this fitting being advantageously provided with a flange *b*⁵ or other means by which the casing *b* may be secured to the lower end of the retort *f* in alignment. Thus a hole of circular shape is formed in the cylindrical wall *b*³ at the position in which the tubular part or fitting *b*⁴ is formed or connected with it, and a tubular part *c*₂ of substantially the same transverse sectional shape as that of the upwardly extending fitting *b*⁴ may be integrally provided or secured to the dish-shaped receptacle *c* and in position in alignment with the tubular part or fitting *b*⁴, the base of the receptacle *c* being provided with an aperture of circular form corresponding to the circular sectional shape of the part or fitting *c*². The tubular part or fitting *c*² has its upper edge formed to a curvature having as its centre the axis upon which the door *a* turns.

Thus it will be understood that the dish-shaped receptacle *c* has at one side of the axle *e* a tubular part *c*² extending upwardly within the casing *b* in alignment with the tubular part or fitting *b*⁴, and that a space is left between the upper edge of the tubular part *c*² and the cylindrical wall *b*³ as well as between the tubular part *c*² and the oppositely disposed lateral walls *b*² of the casing *b*, so as thus to accommodate the cylindrical wall *a*¹ and the oppositely disposed lateral walls *a*² of the door *a* on its being rotated into its closed position. It will furthermore be understood that inasmuch as the lower edges of the cylindrical wall *a*¹ and the lateral walls *a*² of the door are disposed in line, these will pass into the liquid or water seal of the dish-shaped receptacle *c*, on the door assuming the closed position indicated in Figure 1, and inasmuch as the lower edges of the cylindrical wall *b*³ and of the lateral walls *b*² of the casing *b* also extend into the liquid or water seal within the dish-shaped receptacle, the

lower end of the retort is closed with a gas tight seal on the door being moved into its closed position, while on the door being rotated into its open position a clear passage is nevertheless provided through which the charge may pass from the retort through the tubular parts or fittings b^4 and c^2 .

The casing b may be fixedly secured in the position indicated in Figure 1 by any suitable means whereby the lower edge of the cylindrical wall b^3 and of the lateral walls b^2 of the casing are maintained above the bottom of the receptacle c .

I claim:

15 1. In combination with a retort having an opening at the lower end thereof, a closure for said opening comprising in combination a door in the form of a cylindrical sector, a casing of a substantially semi-cylindrical form, said door being mounted within said casing and adapted to rotate partially on the axis of the semi-cylindrical surface of said door from one side of the said casing to the other, the said casing at one side of its cylindrical wall having an aperture in continuation with the lower end of the retort which is closed in one position of the said door and open in the other, and a dish receptacle

30 receptacle in which the lower edges of the cylindrical and lateral walls of the said casing extend and are adapted to be sealed by liquid contained in the said dish receptacle, substantially as described.

2. In combination with a retort having an opening at the lower end thereof, a closure 35 for said opening comprising in combination a door in the form of a cylindrical sector, a casing of a substantially semi-cylindrical form, said door being mounted within said casing and adapted to rotate partially on the 40 axis of the semi-cylindrical surface of said door from one side of the said casing to the other, the said casing at one side of its cylindrical wall having an aperture in continuation 45 with the lower end of the retort which is closed in one position of the said door and open in the other, and a dish receptacle in which the lower edges of the cylindrical and lateral walls of the said casing extend and are adapted to be sealed by liquid contained 50 in the said dish receptacle, said dish receptacle having a tubular part thereon in alignment with the aperture aforesaid, substantially as described.

THOMAS MALCOLM DAVIDSON.
